UNITED STATES PATENT OFFICE.

CHARLES E. HEYER, OF CHICAGO, ILLINOIS, ASSIGNOR TO ARTHUR M. AND ALSON E. BARNHART, BOTH OF SAME PLACE.

DESIGN FOR A FONT OF PRINTING-TYPE.

SPECIFICATION forming part of Design No. 14,959, dated April 15, 1884.

Application filed July 16, 1883. Term of patent 14 years.

To all whom it may concern:

Be it known that I, CHARLES E. HEYER, a citizen of the United States, residing in the city of Chicago, county of Cook, and State of Illinois, have invented and produced a new and original Design for a Font of Printing-Types, of which the following is a specification, reference being had to the accompanying illustration, forming a part hereof.

The character of the design is an extended heavy face; and it consists of capitals, lower-case, figures, points, and one catchword. The letter has a broad appearance running out in diagonal block-like shape, with a hair-line termination. The flags of the capital letters C E F G J L T Z and the lower-case a c g j r y z have an inward decline. The curves of capital C and lower-case c, e, and t swell toward the ending and curve to the inside of the letter.

I claim—

The design for a font of printing-types, as described and shown in the accompanying illustration.

CHARLES E. HEYER.
